(57) **ABSTRACT**

In the coil component, since the contact area between the external terminal electrode and the element body is increased by the protrusion of the external terminal electrode, the external terminal electrode and the element body are more closely attached to each other. Therefore, the attachment strength between the external terminal electrode and the element body can be improved. Hence, it is possible to suppress peeling of the external terminal electrode from the element body.

COIL COMPONENT

TECHNICAL FIELD

The present disclosure relates to a coil component.

BACKGROUND

Well known in the art is a coil component having a coil in an element body thereof. Japanese Patent Application Publication No. 2015-130472 (Patent Document 1) discloses a coil component having four external terminals and provided with two coils in an element body thereof.

SUMMARY

In the above-described coil component, generally, external terminals electrically connected to end portions of the coil are provided on a surface of the element body. If the attachment strength between the element body and the external terminal is low, the external terminal peels off from the element body. Therefore, it is necessary to obtain sufficient attachment strength.

An object of the present disclosure is to provide a coil component in which attachment strength between the element body and the external terminal is improved.

A coil component according to one aspect of the present disclosure includes an element body having a first end surface and a second end surface parallel to each other, an insulating substrate provided in the element body and exposed at the first end surface, the insulating substrate having an exposed region exposed and extending along a first direction at the first end surface, a first coil portion provided on the insulating substrate, the first coil portion having a first end portion exposed at the first end surface, and a first external terminal provided on the first end surface, covering a part of the exposed region of the insulating substrate and the first end portion of the first coil portion. The first external terminal includes a first protrusion protruding toward the exposed region of the insulating substrate along the first direction.

In the above-described coil component, since the contact area between the first external terminal and the element body is increased by the first protrusion of the first external terminal, the first external terminal and the element body are more closely attached to each other. Therefore, it is possible to improve attachment strength between the first external terminal and the element body.

In the coil component according to another aspect of the present disclosure, the first external terminal includes the pair of first protrusions. The pair of the first protrusions protrude oppositely along the first direction.

In the coil component according to another aspect of the present disclosure, the first protrusion is offset from a center position of the first external terminal in a second direction orthogonal to the first direction at the first end surface.

In the coil component according to another aspect of the present disclosure, the first external terminal has an outer shape having a corner portion configured by a curved line.

In the coil component according to another aspect of the present disclosure, the insulating substrate includes a glass cloth.

In the coil component according to another aspect of the present disclosure, the insulating substrate in the exposed region has a surface roughness smaller than a surface roughness of the first end surface of the element body.

2

In the coil component according to another aspect of the present disclosure, the element body further includes a pair of magnetic layers the insulating substrate being sandwiched between the pair of magnetic layers in a second direction orthogonal to the first direction on the first end surface. The insulating substrate has a thickness thinner than a thickness of the magnetic layer with regard to the second direction.

In the coil component according to another aspect of the present disclosure, the element body is composed of a metal magnetic powder-containing resin.

In the coil component according to another aspect of the present disclosure, the element body further includes a mounting surface orthogonal to the first end surface and the second end surface, and a top surface facing the mounting surface. The first external terminal is apart from an edge of the top surface at the first end surface.

In the coil component according to another aspect of the present disclosure, the first external terminal includes a plurality of regions arranged in a second direction orthogonal to the first direction at the first end surface. The plurality of regions includes a first region having the first protrusion, a second region adjacent to the first region on the mounting surface side, and a third region adjacent to the first region on the top surface side. The second region has a length longer than a length of the third region with respect to the first direction.

In the coil component according to another aspect of the present disclosure, the insulating substrate protrudes from the element body at the first end surface.

In the coil component according to another aspect of the present disclosure, a second coil portion is provided on the insulating substrate, having a second end portion exposed at the first end surface. The second external terminal is provided on the first end surface adjacent to the first external terminal in the first direction, covers a part of the exposed region of the insulating substrate and the second end portion of the second coil portion. The second external terminal includes a second protrusion protruding toward the exposed region of the insulating substrate along the first direction. The first protrusion of the first external terminal and the second protrusion of the second external terminal are opposed to each other at the first end surface.

BRIEF DESCRIPTION OF THE DRAWINGS

FIG. 1 is a schematic perspective view of the coil component according to one embodiment.

FIG. 2 is a view showing the inside of the coil component of FIG. 1.

FIG. 3 is an exploded view of the coil shown in FIG. 2.

FIG. 4 is a cross-sectional view of the coil component taken along line IV-IV in FIG. 2.

FIG. 5 is a cross-sectional view of the coil component taken along line V-V in FIG. 2.

FIG. 6 is a plan view of the coil shown in FIG. 2.

FIG. 7 is a view showing one end surface of the element body of the coil component shown in FIG. 1.

FIG. 8 is a view showing the other end surface of the element body of the coil component shown in FIG. 1.

FIG. 9 is a cross-sectional view taken along line IX-IX of FIG. 7.

DETAILED DESCRIPTION

Hereinafter, embodiments of the present disclosure will be described in detail with reference to the accompanying drawings. In the description, the same reference numerals

are used for the same elements or elements having the same functions, and redundant description will be omitted.

The coil component 1 according to one embodiment is, for example, a balun coil. The balun coil is used, for example, when a near field communication circuit (NFC circuit) is mounted on a cellular terminal. The balun coil performs conversion between an unbalanced signal of the antenna and a balanced signal of the NFC circuit, thereby realizing connection between the unbalanced circuit and the balanced circuit. The coil component 1 can be used for a common mode filter or a transformer.

As shown in FIG. 1, the coil component 1 includes an element body 10, a coil structure 20 embedded in the element body 10, and two pairs of external terminal electrodes 60A, 60B, 60C, and 60D provided on the element body 10.

The element body 10 has a rectangular parallelepiped outer shape and has six faces 10a to 10f. As an example, the element body 10 is designed to have dimensions of long side 2.0 mm, short side 1.25 mm, and height of 0.50 mm to 0.65 mm (as an example, 0.65 mm). Among the faces 10a to 10f of the element body 10, the end face 10a (first end face) and the end face 10b (second end face) are parallel to each other, the upper face 10c (mounting face) and the lower face 10d (top face) are parallel to each other, and the side face 10e and the side face 10f are parallel to each other. The lower face 10d faces the upper face 10c. The upper face 10c, the lower face 10d, the side face 10e, and the side face 10f are orthogonal to the end face 10a and the end face 10b. The upper face 10c of the element body 10 faces in a parallel manner a mounting face of a mounting substrate on which the coil component 1 is mounted. In the following description, a direction in which the side faces 10e and 10f face each other is also referred to as a widthwise direction of the element body 10, and a direction in which the upper face 10c and the lower face 10d face each other is also referred to as a height direction of the element body 10.

The element body 10 is made of a metal magnetic powder-containing resin 12 which is one type of magnetic material. The metal magnetic powder-containing resin 12 is a bound powder in which metal magnetic powder is bound by a binder resin. The metal magnetic powder of the metal magnetic powder-containing resin 12 is composed of, for example, an iron-nickel alloy (permalloy alloy), carbonyl iron, an amorphous, FeSiCr alloy in amorphous or crystalline state, sendust, or the like. The binder resin is, for example, a thermosetting epoxy resin. In the present embodiment, the content of the metal magnetic powder in the bound powder is 80 to 92 vol % in terms of volume percent, and 95 to 99 wt % in terms of weight percent. From the viewpoint of magnetic properties, the content of the metal magnetic powder in the bound powder may be 85 to 92 vol % in terms of volume percent and 97 to 99 wt % in terms of weight percent. The magnetic powder of the metal magnetic powder-containing resin 12 may be a powder having one type of average particle diameter or a mixed powder having a plurality of types of average particle diameters.

As shown in FIGS. 2 and 3, the metal magnetic powder-containing resin 12 of the element body 10 integrally covers the coil structure 20 described later. Specifically, the metal magnetic powder-containing resin 12 covers the coil structure 20 from above and below and covers the outer periphery of the coil structure 20. The metal magnetic powder-containing resin 12 fills the inner peripheral region of the coil structure 20. As shown in FIGS. 4 and 5, the metal magnetic powder-containing resin 12 includes a pair of magnetic

portions 12a and 12b (magnetic layers) between which the coil structure 20 is sandwiched in the height direction of the element body 10, and a plurality of magnetic portions 12c interposed between the magnetic portions 12a and 12b. As shown in FIG. 4, the maximum values W_{10a} and W_{10b} and the minimum values W_{20a} and W_{20b} of the thicknesses of the magnetic portions 12a and 12b are the thicknesses of the magnetic portions 12a and 12b along the height direction of the element body 10. The maximum values W_{10a} and W_{10b} of the thickness of the magnetic portions 12a and 12b are the thicknesses of the magnetic portions 12a and 12b at portions where the coil structures 40A and 40B described below are not interposed, for example, the thicknesses of the magnetic portions 12a and 12b at corners defined by the end faces 10a and 10b and the side faces 10e and 10f. The maximum value W_{10a} of the thicknesses of the magnetic portions 12a and the maximum value W_{10b} of the thicknesses of the magnetic portions 12b are, for example, 235 μm to 315 μm . In addition, the minimum values W_{20a} and W_{20b} of the thicknesses of the magnetic portions 12a and 12b are, for example, thicknesses of the magnetic portions 12a and 12b in a portion in which the coil structures 40A and 40B described below are interposed. The minimum value W_{20a} of the thickness of the magnetic portions 12a and the minimum value W_{20b} of the thickness of the magnetic portions 12b are, for example, 80 μm to 270 μm .

The coil structure 20 is embedded in the metal magnetic powder-containing resin 12. The coil structure 20 includes an insulating substrate 30, an upper coil structure 40A provided on an upper side of the insulating substrate 30, and a lower coil structure 40B provided on a lower side of the insulating substrate 30. The plurality of magnetic portions 12c described above are located in the same layer as the insulating substrate 30. The plurality of magnetic portions 12c fill a portion excluding the insulating substrate 30 in the layer in which the insulating substrate 30 is provided. Specifically, a part of the magnetic portion 12c fills an inner peripheral region of the insulating substrate 30, and another part of the magnetic portion 12c fills an outer peripheral region of the insulating substrate 30.

The insulating substrate 30 has a flat plate shape, extends between the end faces 10a and 10b of the element body 10, and is designed to be orthogonal to the end faces 10a and 10b. The insulating substrate 30 extends in parallel to the upper face 10c and the lower face 10d of the element body 10. As shown in FIG. 3, the insulating substrate 30 includes an elliptical ring-shaped coil forming portion 31 extending along the long-side direction of the element body 10, and a pair of frame portions 34A and 34B extending along the short-side direction of the element body 10. The coil forming portion 31 is between frame portions 34A and 34B. The insulating substrate 30 is exposed from the end face 10a of the element body 10 in the frame portion 34A, and the frame portion 34A forms an exposed region R_A exposed in the end face 10a. Similarly, the insulating substrate 30 is exposed from the end face 10b of the element body 10 in the frame portion 34B, and the frame portion 34B forms an exposed region R_B exposed in the end face 10b. An elliptical opening 32 extending along the long-side direction of the element body 10 is provided in a central portion of the coil forming portion 31.

The insulating substrate 30 is made of a nonmagnetic insulating material. In the present embodiment, the insulating substrate 30 has a configuration in which glass cloth is impregnated with epoxy resin. The resin configuring the insulating substrate 30 is not limited to the epoxy-based resin and may be a BT resin, polyimide, aramid, or the like.

The insulating substrate 30 may be made of ceramic or glass. The insulating substrate 30 may be made of a mass-produced printed circuit board material. The insulating substrate 30 may be made of a plastic material used for a BT printed circuit board, an FR4 printed circuit board, or an FR5 printed circuit board.

As shown in FIG. 4, the thickness W_{30} of the insulating substrate 30 can be designed in a range of, for example, 10 μm to 60 μm . The thickness W_{30} of the insulating substrate 30 is, for example, 25 μm . The thickness W_{30} of the insulating substrate 30 can be designed to be thinner than, for example, the minimum value W_{20a} of the thickness of the magnetic portion 12a and the minimum value W_{20b} of the thickness of the magnetic portion 12b. The sum of the maximum value W_{10a} of the thicknesses of the magnetic portions 12a, the maximum value W_{10b} of the thicknesses of the magnetic portions 12b, and the thicknesses W_{30} of the insulating substrates 30 is equal to the height of the element body 10.

The upper coil structure 40A is provided on the upper face 30a of the coil forming portion 31 of the insulating substrate 30. As shown in FIGS. 2 and 3, the upper coil structure 40A includes a first planar coil 41, a second planar coil 42, and an upper insulator 50A. The first planar coil 41 and the second planar coil 42 are wound adjacent to each other in parallel on the upper face 30a of the insulating substrate 30. In this embodiment, the thickness W_{40A} of the upper coil structure 40A is designed to be thicker than the thickness W_{30} of the insulating substrate 30. As shown in FIG. 4, the thickness W_{40A} of the upper coil structure 40A is, for example, 90 μm to 175 μm , and is 110 μm as an example. The sum of the minimum value W_{20a} of the thickness of the magnetic portion 12a and the thickness W_{40A} of the coil structure 40A is the same as the maximum value W_{10a} of the magnetic portion 12a.

The first planar coil 41 is a substantially oval spiral air-core coil wound around the opening 32 of the coil forming portion 31 in the same layer on the upper face 30a of the insulating substrate 30. The number of turns of the first planar coil 41 may be one or a plurality of turns. In the present embodiment, the number of turns of the first planar coil 41 is three to four. The first planar coil 41 has an outer end portion 41a and an inner end portion 41b. The outer end portion 41a is provided on the frame portion 34A and is exposed from the end face 10a of the element body 10. The inner end portion 41b is provided at the edge of the opening 32. The insulating substrate 30 is provided with a first through conductor 41c extending in the thickness direction of the insulating substrate 30 at a position overlapping the inner end portion 41b of the first planar coil 41. The first planar coil 41 is made of Cu, for example, and can be formed by electrolytic plating.

Similarly to the first planar coil 41, the second planar coil 42 is a substantially elliptical spiral air-core coil wound around the opening 32 of the coil forming portion 31 in the same layer on the upper face 30a of the insulating substrate 30. The second planar coil 42 is wound so as to be adjacent to the first planar coil 41 on the inner peripheral side of the first planar coil 41. The number of turns of the second planar coil 42 may be one or a plurality of turns. In the present embodiment, the number of turns of the second planar coil 42 is the same as the number of turns of the first planar coil 41. The second planar coil 42 has an outer end portion 42a and an inner end portion 42b. Similarly to the outer end portion 41a of the first planar coil 41, the outer end portion 42a of the second planar coil 42 is provided in the frame portion 34A and is exposed from the end face 10a of the

element body 10. The inner end portion 42b of the second planar coil 42 is provided at the edge of the opening 32 and is adjacent to the inner end portion 41b of the first planar coil 41. The insulating substrate 30 is provided with a second through conductor 42c extending in the thickness direction of the insulating substrate 30 at a position overlapping with the inner end portion 42b of the second planar coil 42. Similarly to the first planar coil 41, the second planar coil 42 is made of Cu, for example, and can be formed by electrolytic plating.

The upper insulator 50A is provided on the upper face 30a of the insulating substrate 30 and is a thick-film resist patterned by known photolithography. The upper insulator 50A defines a plating growth region of the first planar coil 41 and the second planar coil 42. In the present embodiment, as shown in FIG. 4, the upper insulator 50A integrally covers the first planar coil 41 and the second planar coil 42, and more specifically, covers side faces and upper faces of the first planar coil 41 and the second planar coil 42. As shown in FIGS. 5 and 6, a portion of the upper insulator 50A extends from the inside of the element body 10 to the end face 10a of the element body 10 through between the outer end portion 41a and the outer end portion 42a, and is exposed at the end face 10a. Further, as shown in FIGS. 5 and 6, a part of the upper insulator 50A extends from the inside of the element body 10 to the end face 10b along the upper face 30a and is exposed at the end face 10b. The upper insulator 50A is thicker than the first planar coil 41 and the second planar coil 42. The upper insulator 50A is made of, for example, epoxy.

The lower coil structure 40B is provided on the lower face 30b of the coil forming portion 31 of the insulating substrate 30. As shown in FIGS. 2 and 3, the lower coil structure 40B includes a first planar coil 41, a second planar coil 42, and a lower insulator 50B. The first planar coil 41 and the second planar coil 42 are wound in parallel and adjacent to each other on the lower face 30b of the insulating substrate 30. In the present embodiment, the thickness W_{40B} of the lower coil structure 40B is designed to be thicker than the thickness W_{30} of the insulating substrate 30. As shown in FIG. 4, the thickness W_{40B} of the lower coil structure 40B is, for example, 90 μm to 175 μm , and is 110 μm as an example. The sum of the minimum value W_{20b} of the thickness of the magnetic portion 12b and the thickness W_{40B} of the lower coil structure 40B is the same as the maximum value W_{10b} of the magnetic portion 12b.

The first planar coil 41 and the second planar coil 42 of the lower coil structure 40B are symmetrical to the first planar coil 41 and the second planar coil 42 of the upper coil structure 40A. Specifically, the first planar coil 41 and the second planar coil 42 of the lower coil structure 40B have shapes obtained by inverting the first planar coil 41 and the second planar coil 42 of the upper coil structure 40A around axis parallel to the short sides of the element body 10.

The outer end portion 41a of the first planar coil 41 of the lower coil structure 40B is provided in the frame portion 34B and is exposed from the end face 10b of the element body 10. The inner end portion 41b of the first planar coil 41 of the lower coil structure 40B overlaps the first through conductor 41c provided in the insulating substrate 30. Therefore, the inner end portion 41b of the first planar coil 41 of the lower coil structure 40B is electrically connected to the inner end portion 41b of the first planar coil 41 of the upper coil structure 40A via the first through conductor 41c. The

first planar coil 41 of the lower coil structure 40B is made of Cu, for example, and can be formed by electrolytic plating.

The outer end portion 42a of the second planar coil 42 of the lower coil structure 40B is provided in the frame portion 34B and is exposed from the end face 10b of the element body 10. The inner end portion 42b of the second planar coil 42 of the lower coil structure 40B overlaps the second through conductor 42c provided in the insulating substrate 30. Therefore, the inner end portion 42b of the second planar coil 42 of the lower coil structure 40B is electrically connected to the inner end portion 42b of the second planar coil 42 of the upper coil structure 40A via the second through conductor 42c. The second planar coil 42 of the lower coil structure 40B is made of, for example, Cu, and can be formed by electrolytic plating.

The lower insulator 50B is provided on the lower face 30b of the insulating substrate 30 and is a thick-film resist patterned by known photolithography. Similarly to the upper insulator 50A, the lower insulator 50B defines a plating growth region for the first planar coil 41 and the second planar coil 42. In the present embodiment, as shown in FIG. 4, the lower insulator 50B integrally covers the first planar coil 41 and the second planar coil 42, and more specifically, covers side faces and upper faces of the first planar coil 41 and the second planar coil 42. Similarly to the upper insulator 50A, a portion of the lower insulator 50B extends from the inside of the element body 10 to the end face 10b of the element body 10 through between the outer end portion 41a and the outer end portion 42a, and is exposed at the end face 10b. A portion of the lower insulator 50B extends along the lower face 30b from the inside of the element body 10 to the end face 10a and is exposed at the end face 10a. The lower insulator 50B is thicker than the first planar coil 41 and the second planar coil 42. The lower insulator 50B may have the same thickness as the upper insulator 50A. The lower insulator 50B is made of, for example, epoxy.

The element body 10 includes a pair of coil portions C1 and C2 configuring a double coil structure. The first coil portion C1 includes the first planar coil 41 of the upper coil structure 40A provided on the upper face 30a of the insulating substrate 30, the first planar coil 41 of the lower coil structure 40B provided on the lower face 30b of the insulating substrate 30, and the first through conductor 41c connecting the first planar coils 41 on both faces. In the first coil portion C1, the outer end portion 41a of the first planar coil 41 of the upper coil structure 40A configures a first end portion, and the outer end portion 41a of the first planar coil 41 of the lower coil structure 40B configures a second end portion. The second coil portion C2 is configured to the second planar coil 42 of the upper coil structure 40A provided on the upper face 30a of the insulating substrate 30, the second planar coil 42 of the lower coil structure 40B provided on the lower face 30b of the insulating substrate 30, and the second through conductor 42c connecting the second planar coils 42 on both faces. In the second coil portion C2, the outer end portion 42a of the second planar coil 42 of the upper coil structure 40A configures a first end portion, and the outer end portion 42a of the second planar coil 42 of the lower coil structure 40B configures a second end portion.

The two pairs of external terminal electrodes 60A, 60B, 60C, and 60D are provided in pairs on end faces 10a and 10b of the element body 10 that are parallel to each other.

Of the pair of external terminal electrodes 60A and 60B provided on the end face 10a, the external terminal electrode

60A (first external terminal) is connected to the outer end portion 41a of the first planar coil 41 of the upper coil structure 40A and covers the outer end portion 41a. The external terminal electrode 60B (second external terminal) is connected to the outer end portion 42a of the second planar coil 42 of the upper coil structure 40A and covers the outer end portion 42a. As shown in FIG. 7, the pair of external terminal electrodes 60A and 60B are adjacent to each other in the widthwise direction of the element body 10 and are provided so as to be separated from each other. When viewed from the end face 10a side, the external terminal electrode 60A is biased toward the side face 10f side and covers the end face 10a up to near the edge of the side face 10f. The external terminal electrode 60A is apart from the edge of the lower face 10d in the end face 10a. The external terminal electrode 60B is biased to the side face 10e side, and covers the end face 10a up to near the edge of the side face 10e. The external terminal electrode 60B is apart from the edge of the lower face 10d in the end face 10a.

Of the pair of external terminal electrodes 60C and 60D provided on the end face 10b, the external terminal electrode 60C is connected to the outer end portion 41a of the first planar coil 41 of the lower coil structure 40B, and the external terminal electrode 60D is connected to the outer end portion 42a of the second planar coil 42 of the lower coil structure 40B. As shown in FIG. 8, the pair of external terminal electrodes 60C and 60D are adjacent to each other in the widthwise direction of the element body 10 and are provided so as to be separated from each other. The external terminal electrode 60C is biased to the side face 10f side and covers the end face 10b up to near the edge of the side face 10f. The external terminal electrode 60C is apart from the edge of the lower face 10d in the end face 10b. The external terminal electrode 60D is biased to the side face 10e side, and covers the end face 10b up to near the edge of the side face 10e. The external terminal electrode 60D is apart from the edge of the lower face 10d in the end face 10b.

The external terminal electrode 60A of the end face 10a and the external terminal electrode 60C of the end face 10b are provided at positions corresponding to each other in the long-side direction of the element body 10. Similarly, the external terminal electrode 60B on the end face 10a and the external terminal electrode 60D on the end face 10b are provided at positions corresponding to each other in the long-side direction of the element body 10.

Each of the external terminal electrodes 60A, 60B, 60C, and 60D is bent in an L shape and continuously covers the end faces 10a and 10b and the upper face 10c. In the present embodiment, the external terminal electrodes 60A, 60B, 60C, and 60D are made of resinous electrodes. For example, the external terminal electrodes 60A, 60B, 60C, and 60D made of resins containing Ag powder.

Next, the configuration of the end face 10a of the element body 10 will be described with reference to FIG. 7.

As described above, the insulating substrate 30 is exposed in the exposed region R_A on the end face 10a of the element body 10. The exposed region R_A extends between the side faces 10e and 10f of the element body 10 along a first direction parallel to the upper face 10c and the lower face 10d in the end face 10a. The first direction is the widthwise direction of the element body 10 in the end face 10a. The exposed region R_A is located at a substantially central position of the end face 10a with respect to a second direction orthogonal to the first direction in the end face 10a of the element body 10 (that is, the second direction is a

facing direction of the upper face **10c** and the lower face **10d**, or a height direction of the element body **10** in the end face **10a**.

The external terminal electrode **60A** is located on the side face **10f** side of the end face **10a** and covers a part of the exposed region **R_A**. The external terminal electrode **60A** has a substantially rectangular shape when viewed from the end face **10a** side. More specifically, the external terminal electrode **60A** has a rectangular shape having corner portions formed by curves (that is, having rounded corners). Therefore, the outer shape of the external terminal electrode **60A** does not have a sharp corner portion. More specifically, the external terminal electrode **60A** is configured to three regions arranged in the second direction. Each of the three regions has a rectangular shape extending in the first direction. Of the three regions, the first region **R_{a1}** is located on the exposed region **R_A**. The second region **R_{a2}** is adjacent to the first region **R_{a1}** on the upper face **10c** side. The third region **R_{a3}** is adjacent to the first region **R_{a1}** on the lower face **10d** side. The length of the first region **R_{a1}** along the first direction (i.e., the width **W_{a1}** of the first region **R_{a1}**) is longer than the length of the second region **R_{a2}** along the first direction (i.e., the width **W_{a2}** of the second region **R_{a2}**). Furthermore, the length of the second region **R_{a2}** is longer than the length of the third region **R_{a3}** along the first direction (i.e., the width **W_{a3}** of the third region **R_{a3}**). The length **W_{a1}** of the first region **R_{a1}** is, for example, 500 μm to 600 μm , the length **W_{a2}** of the second region **R_{a2}** is, for example, 400 μm to 500 μm , and the length **W_{a3}** of the third region **R_{a3}** is, for example, 300 μm to 400 μm . When the second region **R_{a2}** is wide, the solder formation region in the vicinity of the mounting substrate is enlarged at the time of solder mounting, so that the mounting strength and electrical connection are stabilized.

The first region **R_{a1}** located on the exposed region **R_A** is located substantially at the center of the end face **10a** in the second direction. The second region **R_{a2}** of the external terminal electrode **60A** reaches the edge of the upper face **10c** in the end face **10a**. On the other hand, the third region **R_{a3}** of the external terminal electrode **60A** does not reach the edge of the lower face **10d** in the end face **10a**, and the lower end of the third region **R_{a3}** is apart from the edge of the lower face **10d** along the second direction. Therefore, the height of the second region **R_{a2}** along the second direction is higher than the height of the third region **R_{a3}**, and the center position **La** of the external terminal electrode **60A** in the second direction is located closer to the upper face **10c** than the center position of the end face **10a**. In other words, the first region **R_{a1}** of the external terminal electrode **60A** is biased toward the lower face **10d** side with respect to the center position **La** of the external terminal electrode **60A** in the second direction.

As described above, the first region **R_{a1}** of the external terminal electrode **60A** is longer in the first direction than the second region **R_{a2}** and the third region **R_{a3}**. Specifically, a portion of the first region **R_{a1}** of the external terminal electrode **60A** that is not in contact with the second region **R_{a2}** and the third region **R_{a3}** configures a pair of protrusions **61a** and **61b** (first protrusions) that protrude in the first direction compared to the second region **R_{a2}** and the third region **R_{a3}**. The pair of protrusions **61a** and **61b** protrude toward the exposed region **R_A** of the insulating substrate **30** along the first direction. The pair of protrusions **61a** and **61b** protrude oppositely along the first direction. Specifically, the protrusion **61a** protrudes in a direction approaching the side face **10e** along the first direction (rightward in FIG. 7). The protrusion **61b** protrudes in a direction approaching the side

face **10f** along the first direction (leftward in FIG. 7). In the present embodiment, since the first region **R_{a1}** is biased toward the lower face **10d** side with respect to the center position **La** of the external terminal electrode **60A** in the second direction, the protrusions **61a** and **61b** of the first region **R_{a1}** are also biased toward the lower face **10d** side with respect to the center position **La** of the external terminal electrode **60A** in the second direction. Each of the protrusion lengths of the protrusions **61a** and **61b** is, for example, 10 μm to 100 μm .

The external terminal electrode **60B** is located on the side face **10e** side of the end face **10a** and covers a part of the exposed region **R_A**. The external terminal electrode **60B** has a substantially rectangular shape when viewed from the end face **10a** side. Specifically, the external terminal electrode **60B** has a rectangular shape having corner portions formed by curves (that is, having rounded corners). Therefore, the outer shape of the external terminal electrode **60B** does not have a sharp corner. More specifically, similarly to the external terminal electrode **60A**, the external terminal electrode **60B** includes three regions arranged in the second direction. Each of the three regions has a rectangular shape extending in the first direction. Of the three regions, the first region **R_{b1}** is located on the exposed region **R_A**. The second region **R_{b2}** is adjacent to the first region **R_{b1}** on the upper face **10c** side. The third region **R_{b3}** is adjacent to the first region **R_{b1}** on the lower face **10d** side. The length of the first region **R_{b1}** along the first direction (i.e., the width **W_{b1}** of the first region **R_{b1}**) is longer than the length of the second region **R_{b2}** along the first direction (i.e., the width **W_{b2}** of the second region **R_{b2}**). Furthermore, the length **W_{b2}** of the second region **R_{b2}** is longer than the length of the third region **R_{b3}** along the first direction (i.e., the width **W_{b3}** of the third region **R_{b3}**). The length **W_{b1}** of the first region **R_{b1}** is, for example, 500 μm to 600 μm , the length **W_{b2}** of the second region **R_{b2}** is, for example, 400 μm to 500 μm , and the length **W_{b3}** of the third region **R_{b3}** is, for example, 300 μm to 400 μm .

The first region **R_{b1}** located on the exposed region **R_A** is located substantially at the center of the end face **10a** in the second direction. The second region **R_{b2}** of the external terminal electrode **60B** reaches the edge of the upper face **10c** in the end face **10a**. On the other hand, the third region **R_{b3}** of the external terminal electrode **60B** does not reach the edge of the lower face **10d** in the end face **10a**, and the lower end of the third region **R_{b3}** is apart from the edge of the lower face **10d** along the second direction. Therefore, the height of the second region **R_{b2}** along the second direction is higher than the height of the third region **R_{b3}**, and the center position **La** of the external terminal electrode **60B** in the second direction is located closer to the upper face **10c** than the center position of the end face **10a**. In other words, the first region **R_{b1}** of the external terminal electrode **60B** is biased toward the lower face **10d** side with respect to the center position **La** of the external terminal electrode **60B** in the second direction. In the present embodiment, the center position **La** of the external terminal electrode **60A** and the center position **Lb** of the external terminal electrode **60B** are at the same height position in the second direction.

As described above, the first region **R_{b1}** of the external terminal electrode **60B** is longer in the first direction than the second region **R_{b2}** and the third region **R_{b3}**. Specifically, a portion of the first region **R_{b1}** of the external terminal electrode **60B** that is not in contact with the second region **R_{b2}** and the third region **R_{b3}** configures a pair of protrusions **62a** and **62b** (second protrusions) that protrude in the first direction compared to the second region **R_{b2}** and the third

region R_{b3} . The pair of protrusions $62a$ and $62b$ protrude toward the exposed region R_A of the insulating substrate 30 along the first direction. The pair of protrusions $62a$ and $62b$ protrude oppositely along the first direction. Specifically, the protrusion $62a$ protrudes in a direction approaching the side face $10f$ along the first direction (leftward in FIG. 7). The protrusion $62b$ protrudes in a direction approaching the side face $10e$ along the first direction (rightward in FIG. 7). In the present embodiment, since the first region R_{b1} is biased toward the lower face $10d$ side from the center position L_b of the external terminal electrode $60B$ in the second direction, the protrusions $62a$ and $62b$ of the first region R_{b1} are also biased toward the lower face $10d$ side from the center position L_b of the external terminal electrode $60B$ in the second direction. In addition, the protrusion $62a$ of the external terminal electrode $60B$ and the protrusion $61a$ of the external terminal electrode $60A$ face each other in the exposed region R_A of the end face $10a$. Specifically, the protrusion $62a$ of the external terminal electrode $60B$ protrudes in the exposed region R_A so as to approach the external terminal electrode $60A$. The protrusion $61a$ of the external terminal electrode $60A$ protrudes in the exposed region R_A so as to approach the external terminal electrode $60B$. Each of the protrusion lengths of the protrusions $62a$ and $62b$ is, for example, 10 μm to 100 μm .

Next, the configuration of the end face $10b$ of the element body 10 will be described with reference to FIG. 8.

The insulating substrate 30 is exposed in the exposed region R_B on the end face $10b$ of the element body 10 . As shown in FIG. 8, the exposed region R_B extends between the side faces $10e$ and $10f$ of the element body 10 along the first direction parallel to the upper face $10c$ and the lower face $10d$ on the end face $10b$ (that is, the widthwise direction of the element body 10 on the end face $10b$) in the same manner as the exposed region R_A on the end face $10a$. The exposed region R_B is located at a substantially central position of the end face $10b$ of the element body 10 with respect to a second direction orthogonal to the first direction in the end face $10b$ of the element body 10 (that is, the second direction is a facing direction of the upper face $10c$ and the lower face $10d$, or a height direction of the element body 10 in the end face $10b$).

The external terminal electrode $60C$ is located on the side face $10f$ side of the end face $10b$ and covers a part of the exposed region R_B . The external terminal electrode $60C$ has a substantially rectangular shape when viewed from the end face $10b$ side. More specifically, the external terminal electrode $60C$ has a rectangular shape having corner portions formed by curves (that is, having rounded corners). Therefore, the outer shape of the external terminal electrode $60C$ does not have a sharp corner. More specifically, the external terminal electrode $60C$ is configured to three regions arranged in the second direction. Each of the three regions has a rectangular shape extending in the first direction. Of the three regions, the first region R_{c1} is located on the exposed region R_B . The second region R_{c2} is adjacent to the first region R_{c1} on the upper face $10c$ side. The third region R_{c3} is adjacent to the first region R_{c1} on the lower face $10d$ side. The length of the first region R_{c1} along the first direction (i.e., the width W_{c1} of the first region R_{c1}) is longer than the length of the second region R_{c2} along the first direction (i.e., the width W_{c2} of the second region R_{c2}). Furthermore, the length W_{c2} of the second region R_{c2} is longer than the length W_{c3} of the third region R_{c3} along the first direction (i.e., the width W_{c3} of the third region R_{c3}). The lengths W_{c1} of the first regions R_{c1} is, for example, 500 μm to 600 μm , the lengths W_{c2} of the second regions R_{c2} is,

for example, 400 μm to 500 μm , and the length W_{c3} of the third region R_{c3} is, for example, 300 μm to 400 μm .

The first region R_{c1} located on the exposed region R_B is located substantially at the center of the end face $10b$ in the second direction. The second region R_{c2} of the external terminal electrode $60C$ reaches the edge of the upper face $10c$ in the end face $10b$. On the other hand, the third region R_{c3} of the external terminal electrode $60C$ does not reach the edge of the lower face $10d$ in the end face $10b$, and the lower end of the third region R_{c3} is apart from the edge of the lower face $10d$ along the second direction. Therefore, the height of the second region R_{c2} along the second direction is higher than the height of the third region R_{c3} , and the center position L_c of the external terminal electrode $60C$ in the second direction is located closer to the upper face $10c$ than the center position of the end face $10b$. In other words, the first region R_{c1} of the external terminal electrode $60C$ is biased toward the lower face $10d$ side with respect to the center position L_c of the external terminal electrode $60C$ in the second direction.

As described above, the first region R_{c1} of the external terminal electrode $60C$ is longer in the first direction than the second region R_{c2} and the third region R_{c3} . Specifically, a portion of the first region R_{c1} of the external terminal electrode $60C$ that is not in contact with the second region R_{c2} and the third region R_{c3} configures a pair of protrusions $63a$ and $63b$ that protrude in the first direction compared to the second region R_{c2} and the third region R_{c3} . The pair of protrusions $63a$ and $63b$ protrude toward the exposed region R_B of the insulating substrate 30 along the first direction. The pair of protrusions $63a$ and $63b$ protrude oppositely along the first direction. Specifically, the protrusion $63a$ protrudes in a direction approaching the side face $10e$ along the first direction (leftward in FIG. 8). The protrusion $63b$ protrudes in a direction approaching the side face $10f$ along the first direction (rightward in FIG. 8). In the present embodiment, since the first region R_{c1} is biased toward the lower face $10d$ side with respect to the center position L_c of the external terminal electrode $60C$ in the second direction, the protrusions $63a$ and $63b$ of the first region R_{c1} are also biased toward the lower face $10d$ side with respect to the center position L_c of the external terminal electrode $60C$ in the second direction. Each of the protrusion lengths of the protrusions $63a$ and $63b$ is, for example, 10 μm to 100 μm .

The external terminal electrode $60D$ is located on the side face $10e$ side of the end face $10b$ and covers a part of the exposed region R_B . The external terminal electrode $60D$ has a substantially rectangular shape when viewed from the end face $10b$ side. Specifically, the external terminal electrode $60D$ has a rectangular shape having corner portions formed by curves (that is, having rounded corners). The outer shape of the external terminal electrode $60D$ does not have a sharp corner. More specifically, similarly to the external terminal electrode $60C$, the external terminal electrode $60D$ includes three regions arranged in the second direction. Each of the three regions has a rectangular shape extending in the first direction. Of the three regions, the first region R_{d1} is located on the exposed region R_B . The second region R_{d2} is adjacent to the first region R_{d1} on the upper face $10c$ side. The third region R_{d3} is adjacent to the first region R_{d1} on the lower face $10d$ side. The length of the first region R_{d1} along the first direction (i.e., the width W_{d1} of the first region R_{d1}) is longer than the length of the second region R_{d2} along the first direction (i.e., the width W_{d2} of the second region R_{d2}). Furthermore, the length W_{d2} of the second region R_{d2} is longer than the length of the third region R_{d3} along the first direction (i.e., the width W_{d3} of the third region R_{d3}). The

length W_{d1} of the first region R_{d1} is, for example, 500 μm to 600 μm , the length W_{d2} of the second region R_{d2} is, for example, 400 μm to 500 μm , and the length W_{d3} of the third region R_{d3} is, for example, 300 μm to 400 μm .

The first region R_{d1} located on the exposed region R_B is located substantially at the center of the end face $10b$ in the second direction. The second region R_{d2} of the external terminal electrode $60D$ reaches the edge of the upper face $10c$ in the end face $10b$. On the other hand, the third region R_{d3} of the external terminal electrode $60D$ does not reach the edge of the lower face $10d$ in the end face $10b$, and the lower end of the third region R_{d3} is apart from the edge of the lower face $10d$ along the second direction. Therefore, the height of the second region R_{d2} along the second direction is higher than the height of the third region R_{d3} , and the center position L_d of the external terminal electrode $60D$ in the second direction is located closer to the upper face $10c$ than the center position of the end face $10b$. In other words, the first region R_{d1} of the external terminal electrode $60D$ is biased toward the lower face $10d$ side with respect to the center position L_d of the external terminal electrode $60D$ in the second direction. In the present embodiment, the center position L_c of the external terminal electrode $60C$ and the center position L_d of the external terminal electrode $60D$ are at the same height position in the second direction.

As described above, the first region R_{d1} of the external terminal electrode $60D$ is longer in the first direction than the second region R_{d2} and the third region R_{d3} . That is, in the first region R_{d1} of the external terminal electrode $60D$, a portion which is not in contact with the second region R_{d2} and the third region R_{d3} configures a pair of protrusions $64a$ and $64b$ which protrude in the first direction compared to the second region R_{d2} and the third region R_{d3} . The pair of protrusions $64a$ and $64b$ protrude toward the exposed region R_B of the insulating substrate 30 along the first direction. The pair of protrusions $64a$ and $64b$ protrude oppositely along the first direction. Specifically, the protrusion $64a$ protrudes in a direction approaching the side face $10f$ along the first direction (rightward in FIG. 8). The protrusion $64b$ protrudes in a direction approaching the side face $10e$ along the first direction (leftward in FIG. 8). In the present embodiment, since the first region R_{d1} is biased toward the lower face $10d$ side with respect to the center position L_d of the external terminal electrode $60D$ in the second direction, the protrusions $64a$ and $64b$ of the first region R_{d1} are also biased toward the lower face $10d$ side with respect to the center position L_d of the external terminal electrode $60D$ in the second direction. In addition, the protrusion $64a$ of the external terminal electrode $60D$ and the protrusion $63a$ of the external terminal electrode $60C$ face each other in the exposed region R_B of the end face $10b$. Specifically, the protrusion $64a$ of the external terminal electrode $60D$ protrudes in the exposed region R_B so as to approach the external terminal electrode $60C$. The protrusion $63a$ of the external terminal electrode $60C$ protrudes in the exposed region R_B so as to approach the external terminal electrode $60D$. Each of the protrusion lengths of the protrusions $64a$ and $64b$ is, for example, 10 μm to 100 μm .

The cross section of the end faces $10a$ and $10b$ will be described with reference to FIG. 9. Since the cross section of the end face $10b$ is identical or similar to the cross section of the end face $10a$, the description thereof is omitted.

As shown in FIG. 9, the end face $10a$ is provided with a protruding portion $35A$ where the frame portion $34A$ of the insulating substrate 30 protrudes from the end face $10a$. The protruding portion $35A$ has a protrusion length W_{35A} of, for example, 10 μm to 30 μm . That is, a portion of the insulating

substrate 30 corresponding to the first region R_{a1} among the three regions R_{a1} , R_{a2} , and R_{a3} protrudes. The thickness of the external terminal electrode $60A$ is not uniform with reference to the end face $10a$, and is different in each of the three regions R_{a1} , R_{a2} , and R_{a3} as shown in FIG. 9. Specifically, the external terminal electrode $60A$ has a minimum thickness $T1$ at the lower end of the third region R_{a3} closer to the lower face $10d$ and a maximum thickness $T2$ near the center of the second region R_{a2} in the second direction. The thickness of the external terminal electrodes $60A$ monotonically increases from the lower end portion of the third region R_{a3} to the vicinity of the center of the second region R_{a2} and then monotonically decrease to the upper face $10c$. However, since the exposed region R_A of the frame portion $34A$ protrudes in a direction orthogonal to the end face $10a$ in the end face $10a$, the thickness $T3$ of the external terminal electrodes $60A$ in the exposed region R_A is reduced by the lengths W_{35A} of the protruding portion $35A$. The minimum thickness $T1$ is, for example, 10 μm , and the maximum thickness $T2$ is, for example, 40 μm .

The protruding portion $35A$ of the end face $10a$ is generated by the metal magnetic powder-containing resin 12 in the end face $10a$ receding from the end face $10a$ in manufacturing the element body 10 . More specifically, by cutting the plurality of element bodies 10 integrally formed, the element bodies 10 are separated from each other. The end face $10a$ with flat plane is formed as a face generated by the cutting. Then, a surface treatment (including an etching treatment or the like) such as barrel polishing is performed on each element body 10 , and the metal magnetic powder-containing resin 12 which is relatively easily polished on the end face $10a$ is polished. By the polishing, a region other than the exposed region R_A in the end face $10a$ retreats in the direction orthogonal to the end face $10a$, and thus a part of the frame portions $34A$ and $34B$ relatively protrudes from the end face $10a$ and becomes the protruding portion $35A$. In the end face $10a$, the roughness of the exposed region R_A after polishing is smaller than the roughness of the magnetic portion $12a$ and the magnetic portion $12b$.

In the present embodiment, since the contact areas between the external terminal electrode $60A$ and the element body 10 are increased by the protrusion $61a$ and the protrusion $61b$ of the external terminal electrode $60A$, the external terminal electrode $60A$ and the element body 10 are more firmly attached to each other. Therefore, the attachment strength between the external terminal electrode $60A$ and the element body 10 can be improved. Similarly, the external terminal electrodes $60B$, $60C$, and $60D$ can also improve the attachment strength with the element body 10 . As described above, it is possible to prevent the external terminal electrodes $60A$, $60B$, $60C$, and $60D$ from peeling off from the element body 10 .

In addition, in the present embodiment, the external terminal electrodes $60A$, $60B$, $60C$, and $60D$ have a curved outer shape with no corners. Here, in the case that the outer shape has a sharp corner, when external stresses are applied to the external terminal electrodes $60A$, $60B$, $60C$, and $60D$, the external terminal electrodes $60A$, $60B$, $60C$, and $60D$ are likely to peel off from the corner as a starting point. Therefore, according to the configuration of the present embodiment, it is possible to prevent the external terminal electrodes $60A$, $60B$, $60C$, and $60D$ from peeling off from the element body 10 .

In the present embodiment, the frame portion $34A$ of the insulating substrate 30 protrudes from the element body 10 at the end face $10a$. The frame portion $34B$ of the insulating substrate 30 protrudes from the element body 10 at the end

15

face **10b**. This increases the face areas of the end faces **10a** in the protruding portion **35A**, thereby increasing the contact areas with the external terminal electrodes **60A**, **60B**, **60C**, and **60D**, so that the element body and the external terminal electrode are more firmly brought into contact with each other. Therefore, the attachment strength between the external terminal electrode **60A** and the element body **10** can be improved. As described above, it is possible to prevent the external terminal electrodes **60A**, **60B**, **60C**, and **60D** from peeling off from the element body **10**.

Although the embodiments of the present disclosure have been described above, the present disclosure is not necessarily limited to the above-described embodiments, and various modifications can be made without departing from the scope of the summary of the present disclosure. For example, the number of coils is not limited to two, and may be three or more. The number of external terminal electrodes in each of the end faces **10a** and **10b** is not limited to two, and may be one or three or more. The first regions R_{a1} , R_{b1} , R_{c1} , and R_{d1} are offset from the center positions La , Lb , Lc , and Ld of the external terminal electrodes **60A**, **60B**, **60C**, and **60D** toward the lower face **10d**, but may coincide with the center positions La , Lb , Lc , and Ld , or may be offset toward the upper face **10c**. The upper insulator **50A** and the lower insulator **50B** are exposed at the end faces **10a** and **10b**, but may not be exposed. The center positions La and Lb may be located at the same height or may be located at different heights. The center positions Lc and Ld may be located at the same height or may be located at different heights. In each of the external terminal electrodes **60A**, **60B**, **60C**, and **60D**, the number of protrusions is not limited to two and may be one or three or more.

What is claimed is:

1. A coil component comprising:

an element body having a first end face and a second end face that are parallel to each other;
an insulating substrate provided in the element body and exposed at the first end face, the insulating substrate having an exposed region exposed and extending along a first direction at the first end face;
a first coil portion provided on the insulating substrate, the first coil portion having a first end portion exposed at the first end face; and
a first external terminal provided on the first end face, covering a part of the exposed region of the insulating substrate and the first end portion of the first coil portion,
wherein the first external terminal includes a first protrusion protruding toward the exposed region of the insulating substrate along the first direction,
wherein the element body further includes a mounting face orthogonal to the first end face and the second end face, and a top face facing the mounting face,
wherein the first external terminal is apart from an edge of the top face at the first end face,
wherein the first external terminal includes a plurality of regions arranged in a second direction orthogonal to the first direction at the first end face,
wherein the plurality of regions includes a first region having the first protrusion, a second region adjacent to

16

the first region on the mounting face side, and a third region adjacent to the first region on the top face side, and

wherein the second region has a length longer than a length of the third region with respect to the first direction.

2. The coil component according to claim 1, wherein the first external terminal includes a pair of the first protrusions, and

10 wherein the pair of the first protrusions protrude oppositely along the first direction.

3. The coil component according to claim 1, wherein the first protrusion is offset from a center position of the first external terminal in a second direction orthogonal to the first direction at the first end face.

4. The coil component according to claim 1, wherein the first external terminal has an outer shape having a corner portion configured by a curved line.

20 5. The coil component according to claim 1, wherein the insulating substrate includes glass cloth.

6. The coil component according to claim 1, wherein the insulating substrate in the exposed region has a surface roughness smaller than a surface roughness of the first end face of the element body.

25 7. The coil component according to claim 1, wherein the element body further includes a pair of magnetic layers, the insulating substrate being sandwiched between the pair of magnetic layers in a second direction orthogonal to the first direction at the first end face, and

30 wherein the insulating substrate has a thickness thinner than a thickness of the magnetic layer with regard to the second direction.

8. The coil component according to claim 1, wherein the element body is composed of a metal magnetic powder-containing resin.

40 9. The coil component according to claim 1, wherein the insulating substrate protrudes from the element body at the first end face.

10. The coil component according to claim 1, further comprising:

45 a second coil portion provided on the insulating substrate, having a second end portion exposed at the first end face; and

50 a second external terminal provided on the first end face adjacent to the first external terminal in the first direction, covering a part of the exposed region of the insulating substrate and the second end portion of the second coil portion,

55 wherein the second external terminal includes a second protrusion protruding toward the exposed region of the insulating substrate along the first direction, and

wherein the first protrusion of the first external terminal and the second protrusion of the second external terminal are opposed to each other at the first end face.
